UNITED STATES PATENT OFFICE.

WILBER C. BELKNAP, OF NEW YORK, N. Y.

CUSHION-CAP FOR TYPEWRITER-KEYS.

1,364,828.

Specification of Letters Patent.

Patented Jan. 4, 1921.

Application filed October 30, 1919. Serial No. 334,421.

To all whom it may concern:

Be it known that I, WILBER C. BELKNAP, a citizen of the United States, residing at New York, in the county of New York and 5 State of New York, have invented certain new and useful Improvements in Cushion-Caps for Typewriter-Keys, of which the following is a specification, reference being had therein to the accompanying drawing.

10 This invention relates to improved cushion caps for typewriter keys, and has for its particular object to provide a cushion cap which may be applied to and detached from the keys more readily than the well known 15 devices of this character now in common use.

An object of the invention is to provide a cushion cap having a resilient or tension element which yields sufficiently but not excessively when the cushion cap is applied to 20 a key to allow the cap to slip over the key readily, the resilient or tension element then acting to hold the cap securely on the key. To this end, the present invention is a substantial improvement over certain well 25 known cushion caps now in general use, and it is a further improvement with respect to simplicity and cheapness of construction and, as stated, with respect to the ease with which it can be applied and removed from 30 the typewriter keys.

In the accompanying drawings:

Figure 1 is a top plan view of a typewriter key provided with a cushion cap of the present invention;

35 Fig. 2 is a bottom plan view of the parts shown in Fig. 1;

Fig. 3 is a cross-sectional view taken centrally of Fig. 1 on the line 3—3.

40 Fig. 4 is a detail in cross section of the cushion cap taken on the line 4—4 of Fig. 2;

Fig. 5 is a detail in cross section of modified form of the cushion cap shown in Fig. 4;

45 Fig. 6 is a sectional view of a further modification of the cushion cap shown in Fig. 4;

Fig. 7 is a detail view of the spring clip used in connection with the modified forms of cushion pad shown in Figs. 5 and 6; and

50 Fig. 8 is a perspective view of my preferred form of cushion cap.

The improved cushion caps may be made in any size and shape to fit the keys of any typewriter or other writing machine. As shown in the drawings, 1 represents the key bar, 2 a finger key of standard size and shape, having the usual raised outer edge 3.

The cushion cap consists of an upper cushion portion 4, preferably made of rubber of any suitable thickness and resiliency to produce the desired cushion effect to the 60 touch of the fingers of the operator.

The lower portion of the cap consists of a resilient web or diaphragm 5, having a slot 6 formed therein to receive the key bar, the part 5 being joined to this part 4 by a 65 resilient side portion 7, and extending inwardly substantially beyond the center of the cap. Thus a pocket or space 8 is formed by the portions 4, 5 and 7 adapted to receive the typewriter key therebetween, the cap 70 being slipped over the key from the front thereof, the slot 6 passing about the key bar to permit of the cap being seated centrally over the key. A downwardly extending resilient edge 9 formed on the under side of 75 the part 4 overlaps the edge of the portion of the key not engaged by the part 7, thus serving to bring the entire upper portion of the key under lateral pressure of the resilient elements, vertical pressure being exerted 80 on the key also by the combined resiliency of the parts 4, 5 and 7, serving thus to hold the cushion cap securely on the key, but permitting the easy removal thereof.

In the form of the cushion cap shown in 85 Figs. 3 and 4, a space 10 will be formed between the cushion part 4 and the depressed portion of the key 2. This space being filled with air will add to the cushion effect of part 4 when finger pressure is exerted 90 thereon.

In the modified form of the cap shown in Fig. 5, the depression 10 is occupied by a downward projection 11 of the cushion 4, an annular groove 12 being formed between 95 the parts 7 and 11 adapted to receive the rim 3 of the typewriter key.

Either arrangement shown in Figs. 4 and 5 have been found practicable, on account of its increased thickness the latter being 100 slightly more firm than the former.

The modified forms of cushion caps shown in Figs. 5 and 6, is in effect substantially the same as the form shown in Figs. 1 to 4, although the construction of the several parts 105 is quite different with respect to the means for securing the cap to the typewriter key.

As here shown the modified cap consists of a cushion portion 13, having a peripheral groove 14, a downwardly projecting edge 110 15 and a depressed portion 16 formed respectively in the side and bottom thereof.

The edge 15 is adapted to be seated within the edge 3 of the typewriter key, and the groove 14 is adapted to be engaged by the loop portion 17 of a spring clip which serves 5 to secure the cushion to the key, the clip having downwardly and rearwardly projecting prongs 18 which engage the key bar on the opposite sides thereof and, by exerting pressure or spring tension on the key, serve to 10 hold the cushion cap securely thereon. To prevent forward movement of this clip relative to the key, the free ends of the prongs 18 are bent upwardly to engage the key as shown at 19.

15 From the foregoing detailed description, the construction of my improved cushion cap in the several forms here shown and the means of securing the same to the keys of writing machines will be readily understood.

20 The principle of the several forms is substantially the same, as defined in the appended claims.

Having thus fully described my invention, what I claim as new and desire to secure by 25 Letters Patent, is:

1. The combination with a typewriter key, of a cushion cap having a depression formed in the under side thereof adapted to be occupied by a portion of said key, a horizontal 30 resilient web under portion, slotted to receive the key bar, and spaced from said cushion by a resilient intermediate portion to receive said key therebetween.

2. The combination with a typewriter key, 35 of a resilient cushion cap having formed on the under side thereof a downwardly projecting resilient edge and an intermediate resilient portion adapted to engage respectively the upper edge and side of said key, a horizontal resilient web under portion spaced from the cushion and slotted to receive the key-bar therebetween, and connected to the cushion by said intermediate resilient portion whereby the cushion cap 40 may be detachably mounted on said key.

45 3. The combination with a typewriter key

of a cushion cap adapted to telescope a portion of said key, and having a lower slotted portion adapted to extend on opposite sides of and embrace the key bar, being spaced 50 from the cushion by an intermediate yielding connection to receive the key therebetween whereby the cushion cap may be detachably mounted on said key.

4. The combination with a typewriter key 55 of a circular shaped resilient cushion cap adapted to engage with the upper portion of the key, a semi-circular resilient web portion extending substantially beyond the center of the key with a radial slot in the edge 60 thereof to receive and embrace the key-bar, said web portion being spaced from the cushion cap by a resilient intermediate portion adapted to receive the key therebetween.

5. The combination with a typewriter key, 65 of a cushion cap adapted to be mounted substantially flush with the upper edge of said key, a resilient member extending from the inner base of the cushion cap and resting flat against the face of the key, a resilient 70 under element spaced from the cushion and adapted to embrace and receive the key bar.

6. The combination with a typewriter key, 75 of a cushion pad adapted to engage with the upper portion of said key and to exert lateral pressure thereon, and having a tension element adapted to extend over the sides and across the bottom of the key on opposite sides of the key bar and exerting upward pressure on the key whereby the 80 cushion pad by the combined pressure of said parts is held on said key.

7. A cushion pad for a typewriter key consisting of a circular-shaped resilient cushion adapted to engage a portion of said key, a semi-circular-shaped resilient web secured to and spaced from said cushion substantially in the plane thereof, and having a radial slot formed in the edge thereof to receive and embrace the key bar. 85

In testimony whereof, I affix my signature.
WILBER C. BELKNAP
